CALENDER ROLLS

Howard E. Kuehn, Orange, Conn., assignor to Farrel-Birmingham Company, Incorporated, Ansonia, Conn.
Filed Oct. 23, 1962, Ser. No. 232,547
10 Claims. (Cl. 29—121)

This invention relates to calenders and like devices and more particularly relates to compensation of calender rolls to control the effective crown thereon.

In machines such as calenders designed for rolling relatively thin sheet material, one or more rolls of the calender may be designed with a crown thereon in order to compensate for the bending and deflection of the rolls intermediate their ends due to the considerable pressure exerted upon these rolls during operation. The degree of crown given to the rolls is selected to be that which will bring about a substantially parallel arrangement of the cooperating roll surfaces during operation thereof. The degree of crown with which the rolls will be provided depends upon the pressure under which they operate plus other operating conditions which may include the type of material being rolled as well as the characteristics and dimensions of the rolls. Therefore, for optimum results it may be necessary to provide rolls with different crowns for different operating conditions.

Where calendering machines are required to roll different types of sheet material the crown provided on the rolls may be the optimum crown for one of the materials while the same crown would not be the optimum for other materials.

To provide various crowns on calender rolls for various operating conditions of the calender the effective crown of the rolls may be varied by crossing the axes of cooperating rolls so that the axes of the crossed rolls form equal acute angles and the rolls are wider spaced at their ends than at their center. To accomplish roll axis crossing, at least one of two cooperating rolls is moved about a point intermediate the roll ends so as to bring about a nonparallel relation of the roll axes to effect what is commonly termed, a cross-axis relationship. A calender having facility for crossing the axes of cooperating rolls is disclosed and claimed in United States Patent 2,965,920 of Warren C. Whittum, assigned to the same assignee as the present application.

Another technique of providing crown compensation of calender rolls is to bend the rolls so as to provide an effective crown thereon. Roll bending may be accomplished by exerting forces on the roll necks outboard of their point of support in the calender frame. The forces exerted on the roll necks act in the same direction to produce a bending moment of the roll about its points of support and may be in such a direction as to either provide a convex working surface on the roll or a concave one. A calender having facility for roll bending is disclosed in U.S. Patent 2,611,150.

Both of aforementioned techniques of crown control, axis crossing and roll bending, provide an effective crown on a roll which in many applications is satisfactory, however, neither of these techniques of crown compensation give an effective crown contour equal to the optimum crown contour that would be utilized if an optimum crown contour could be selected for each operating condition of the calender. An optimum crown contour, as hereinafter pointed out, has been well established by theoretical and empirical techniques and is quite well known to those skilled in the art of calendering operations. If the crown contour or the effective crown contour is not within a given tolerance which may be very small, then a substantially uniform nip pressure across the faces of the cooperating calender rolls is not ob-

2

tained and varying degrees of unsatisfactory operation may occur dependent upon the tolerances allowed in the thickness of the sheet material rolled by the calender. For example, if a calender is rolling a very thin sheet of material, a deviation in the thickness of the material of several ten-thousandths of an inch can be very critical, whereas in rolling a thick sheet or board such deviation would be insignificant.

Many times, in practice, the most critical material to be rolled on a calender needing the most accurate total crown, is not rolled at the particular crown on the roll as ground, i.e., the original crown. Therefore, the original crown requires modification which may be provided by roll axis crossing or roll bending. Such modification, however, provides an effective crown contour which departs from the desired crown contour.

By practice of the present invention, a calender roll arranged for cross-axis or roll-bending crown control may be properly compensated to provide an effective crown corresponding to a desired crown contour. The present invention provides calender rolls having a crown contour which compensates for deviations in an effective crown obtained by crossing the axes of cooperating rolls or roll bending.

Accordingly, it is a primary object of this invention to provide rolls for a calendering machine which may have an effective crown established therebetween which coincides very precisely with a desired crown contour necessary to maintain a uniform pressure on material being rolled across the width thereof.

In accordance with this invention, calender rolls are so contoured that if it should be desired to vary the effective crown thereon as for example, by roll-axis crossing or roll bending, the effective crown provided thereby on cooperating rolls will very accurately coincide with an optimum crown contour selected in accordance with the deflection curve of a loaded beam.

The novel features of the invention are pointed out with particularly in the claims appended to and forming part of this specification. However, the invention, as to its organization, together with further objects and advantages thereof, may best be appreciated by reference to the following description taken in conjunction with the drawings wherein:

FIG. 1 illustrates, in front elevation, the rolls of a calendar.

FIG. 2 is a view seen along line 2—2 of FIG. 1 with the axis of the bottom roll crossed with respect to the roll immediately above.

FIG. 3 is an end view of the calender rolls of FIG. 2.

FIG. 4 illustrates the effective crown obtained on a calender roll by roll axis crossing.

FIG. 5 illustrates crown contours obtained by roll axis crossing and an optimum crown contour originally ground on a calender roll in accordance with a calculated deflection curve.

FIGS. 6 and 7 illustrate calender rolls provided with crowns in accordance with the invention.

FIG. 8 illustrates, in front elevation, the rolls of a calender wherein the lower roll is adapted to have an effective crown provided thereon by roll bending.

FIGS. 9 and 10 illustrate lower calender rolls having effective crown provided thereon by roll bending.

FIG. 11 illustrates the effective crown provided on a roll by roll bending.

FIG. 12 illustrates a calender roll adapted for roll bending and having a compensated crown contour in accordance with the invention.

FIG. 13 is a graphic illustration of a crown contour obtained through roll bending.

The primary objective in crowning rolls is to com-

pensate for bending of the rolls intermediate their ends under the considerable pressure exerted on these rolls during operation of the rolls and thus obtain a uniform distribution of pressure at the roll nip. The crown shape recommended and used as an optimum or target curve for a calender roll is illustrated by curve C, FIG. 5, and the degree of crown at points along its length are expressed in terms of the maximum crown as hereinafter exemplified. This optimum or target curve is determined from the general equation for the deflection of a symmetrical beam on two supports with a distributed load evenly spaced therebetween which may be found in "Machinery's Handbook," 16th Edition, page 398, and hereinafter will be referred to as a deflection-curve crown. In the example given below in Table I, the deflection-curve crown illustrated is for a roll having an A/L ratio, as illustrated in FIG. 1, of .12, where L is the length of the roll face and A is the distance from the ends of the roll face to the center lines of support of the roll journals.

Table I

Fraction of distance from end of roll to center	Fraction of total crown
.0	0
.1	.1705
.2	.3307
.3	.4783
.4	.6108
.5	.7262
.6	.8229
.7	.8990
.8	.9551
.9	.9887
1.0	1.000

The crown curve for a calender roll having an A/L value of .12 was selected for illustration inasmuch as this value is the one most commonly used in industry. For further example, the percent of total crown of a deflection-curve crown at the point midway between the end of a roll and the center line thereof will vary between .7209 and .7309 of the maximum crown for A/L values between .06 and .20. A general discussion on roll crowning may be found in "Paper Trade Journal," July 18, 1960, pages 36-42.

If a calender is to process but one material of given thickness, an optimum or deflection-curve crown may be selected and satisfactory results will be obtained. However, since most mills, particularly in the paper industry, must produce different grades and widths of material, the application of crowns to rolls often becomes a compromise dictated by the range of materials to be rolled. It is, of course, much better to base a compromise on exact knowledge of what the correct conditions should be, because conditions can then be altered with greater certainty of obtaining the best results.

The effective crown curve of a roll may be varied by crossing the axis of one roll with respect to another as explained in U.S. Patent 2,965,920, assigned to the same assignee as the present invention, however, the effective crown obtained by roll axis crossing varies from the deflection-crown curve with resulting nonuniformity in nip pressure between the rolls.

To illustrate the deviation between an effective crown obtained by roll axis crossing and the crown corresponding to the deflection curve, consider the calender 14 of FIG. 1, having a bottom roll 15 and pressure rolls 16-21 thereupon. Let it be assumed that the bottom roll 15 is cylindrical and arranged to have its axis 22 crossed with respect to axis 23 of roll 16, also assumed to be cylindrical, as illustrated in FIG. 2.

With reference to FIG. 2 and FIG. 3, which is a diagrammatic end view of the rolls of FIG. 2, let

y =distance or gap between surfaces of crossed axis rolls
 D =distance between axis of rolls in uncrossed condition
 C_T =horizontal distance between crossed axes at end of rolls

L =Length of roll

x =an arbitrary distance from end of roll

C =horizontal distance between crossed axis 22 and 23 at distance x

then

$$\frac{C_T}{L} = \frac{C}{\frac{L}{2} - \frac{x}{2}} \quad (1)$$

10 and

$$C = C_T \left(1 - \frac{2x}{L} \right) \quad (2)$$

then

$$y + D = \sqrt{C_T^2 \left(1 - \frac{2x}{L} \right)^2 + D^2} \quad (3)$$

15 if for purposes of illustration $D=20''$ and $C_T=1''$

$$y = \sqrt{\left(1 - \frac{2x}{L} \right)^2 + 400 - 20} \quad (4)$$

The effective crown contour which may be determined from Equation 4 is shown in Table II below.

Table II

Fraction of distance along roll from end to center is	Gap y , in.	Fraction of total effective crown	Deflection curve crown from Table I
0	.0249	0	0
.10	.0203	.185	.170
.20	.0159	.361	.331
.30	.0122	.510	.478
.40	.0089	.642	.611
.50	.0062	.751	.726
.60	.0040	.839	.823
.70	.0022	.912	.899
.80	.0010	.960	.955
.90	.0002	.992	.989
1.00	0	1.0	1.0

40 It will be noted that the effective crown curve obtained from roll axis crossing as exemplified by curve B, FIG. 5, varies appreciably from the optimum or deflection curve crown as exemplified by curve C, FIG. 5, particularly, intermediate the center and end of the roll as is further evidenced by comparison of the crown contours of Tables I and II. In FIG. 5, the point one half of the distance from the end of the roll to the center has been selected to numerically indicate the deviation of an effective crown contour from deflection-curve crown contour.

45 Therefore, in accordance with the invention where a calender is provided having facility for cross-axis crown control, it will be modified by the difference in the target or deflection curve and the effective crown contour as exemplified by the difference in crown curves C and B, FIG. 5.

50 FIG. 4 illustrates a pair of cooperating rolls 24 and 25 wherein the bottom roll 25 is arranged to have its axis crossed with respect to the axis of roll 24. In FIG. 4, roll 25 which originally was ground with a deflection-curve crown and, when utilized with its axis crossed with respect to roll 24, produces an undesired effective crown 26, as illustrated, and uniform nip pressure will not be achieved across the face of the rolls 24 and 25 and the material M being rolled will not attain a uniform thickness. It may be noted that there will be high areas 27 and 28 in the effective crown 26 intermediate the ends and the center of the rolls.

55 FIG. 6 illustrates a calender roll 29 having a crown ground thereon, in accordance with the deflection curve, as exemplified by broken line 30, modified by the difference in the deflection-curve crown and the effective crown obtained by roll axis crossing, as exemplified by the full line crown. The deflection-curve crown is indicated by 70 the reference numeral 30, and the final modified crown

curve is indicated by the reference numeral 31. It will be noted that the roll 29 of FIG. 6, in accordance with the invention has some of the deflection-curve crown removed in the areas corresponding to the difference between crown curves C and B, FIG. 5.

FIG. 7 illustrates the manner in which a normally cylindrical roll 32 adapted for cross axis operation will have its crown contour 33 modified from a cylindrical shape 34 in accordance with the invention so that when it is operated with its axis crossed, an effective crown equivalent to the deflection-curve crown will be obtained.

It is to be understood that throughout the drawings, for clarity of illustration, the crown contours are exaggerated.

It may also be shown that the effective crown obtained by roll bending, as exemplified in FIGS. 8 and 9, deviates from the deflection-curve crown contour as determined by the beam deflection method, and the invention also contemplates compensation for such deviation. A calendar having facility for roll bending or unbending to vary the effective crown of a roll is disclosed in U.S. Patent 2,611,150.

FIG. 8 illustrates a calender 35 comprising a bottom roll 36 having journals 37a and 37b which support roll 36 at points equidistant from each end of the face thereof on bearings 38 and 39. Pressure rollers 40-45 are mounted vertically above roll 36. Roll 36 is arranged to be bent by forces applied to the extending ends of its journals equidistant from the center of support of journals 37a and 37b, as represented by the downwardly directed vectors 46 of equal magnitude and the upwardly directed vectors 47 of equal magnitude. FIG. 9 illustrates bending of roll 36 by application of downwardly directed forces on the extending ends of its journals to provide an effective crown curve 48 thereon. It will be noted that the applied forces 46, together with the reaction exerted on the journals by bearings 38 and 39 produce oppositely directed force couples at either end of the roll.

The face of roll 36 when roll 36 is bent, as illustrated in FIG. 9, is shown in FIG. 13 set on a coordinate x-y axis. The contour of the crown on the roll 36 resulting from roll bending will be a true arc of a circle of radius R where

$$R = \frac{EI}{M} \quad (1)$$

It may be shown that

$$\frac{dy}{dx^2} = \frac{M}{EI} \quad (2)$$

where

E=modulus of elasticity of the roll

I=moment of inertia

M=bending moment

See "Mechanics of Material," Lawson and Cox, 2nd edition, 1950, Wiley and Sons, pp. 155-158.

then

$$\frac{dy}{dx} = \frac{Mx}{EI} + C_1 \quad (3)$$

and

$$y = \frac{Mx^2}{2EI} + C_1x + C_2 \quad (4)$$

when

$$x=0, y=0$$

$$x = \frac{L}{2}, \frac{dy}{dx} = 0$$

therefore

$$C_2 = 0 \text{ and } C_1 = -\frac{ML}{2EI} \quad (5)$$

and

$$y = \frac{M}{2EI}(x^2 - Lx) \quad (6)$$

5 at

$$x = \frac{L}{2}$$

$$y \text{ max.} = f = \frac{M}{2EI} \cdot \frac{L^2}{4} = \frac{ML^2}{8EI} \quad (7)$$

from the foregoing

$$\frac{M}{2EI} = \frac{4f}{L^2} \quad (8)$$

15 substituting (9) in (7)

$$y = \frac{4f}{L^2}(x^2 - Lx) = 4f \left[\left(\frac{x}{L} \right)^2 - \frac{x}{L} \right] \quad (9)$$

20 which gives the contour of a crown curve for a given total crown f where the crown is formed on a radius.

Therefore, the effective crown produced by bending a cylindrical roll, expressed as a percentage of total crown f is as shown in Table III.

Table III

	Fraction of distance from end of roll to center	Fraction of total crown	Crown curve due to axes crossing (from Table II)
30	0	0	0
	.10	.190	.185
	.20	.380	.361
	.30	.510	.510
	.40	.640	.642
	.50	.750	.751
35	.60	.840	.830
	.70	.910	.912
	.80	.960	.960
	.90	.990	.992
	1.00	1.000	1.000

40 It will be noted that the effective crown contour obtained by roll bending is almost identical to the effective crown contour obtained by crossing roll axes as pointed out in Table II. Therefore, for purpose of discussion, curve B of FIG. 5 may be considered to also represent an effective crown due to roll bending.

45 In some instances the crown on a roll may be decreased by roll unbending as illustrated in FIG. 10 to obtain a net crown 49 of less magnitude than initially applied to the roll 36. The purpose of unbending the roll is to reduce the magnitude of the original crown on the roll by an amount required to obtain a smaller magnitude crown for rolling a material requiring less nip pressure. However, unless the roll 36 has a crown contour properly compensated for roll bending, the resulting crown 50 55 would appear as shown in FIG. 11 and the nip pressure between the faces of rolls 36 and 40 will not be uniform across the faces thereof and the material M being rolled will not have a uniform thickness.

FIG. 12 illustrates a roll 51, contoured in accordance with the invention, arranged for roll unbending or uncrowning crown compensation as exemplified in FIG. 10. The contour or outline of roll 51 is a composite of a deflection-curve crown in accordance with the deflection curve, as exemplified by the broken line 52, with additional crown 53, 54 superimposed thereon to provide an effective crown on roll 51, which in roll unbending operation would achieve the contour of the desired deflection-curve crown. In FIG. 12, the additional crown 53, 54 added to deflection curve crown 52 is the difference in the crown contours of Tables I and III.

50 If a calendar roll having the normal deflection-curve crown contour were to be used for roll bending crown control as exemplified by FIG. 9, it would, in accordance with the invention, have a crown provided thereon derived from subtracting the difference of the crown con-

tours of Tables I and III from the deflection-curve contour of Table I which would produce a crown contour as exemplified in full line in FIG. 6.

In the crown contours discussed, the total magnitude of a given crown on a calender roll has not been specifically discussed and it will be apparent that the absolute magnitude of a given crown will depend on such parameters as the dimensions of the roll, the pressure exerted thereon, etc. For purposes of illustration only, where a roll has an effective crown change as a result of roll axis crossing or roll bending which amounts to ".020" at a distance midway between the center and end of the roll face, the difference between curves 30 and 31 (FIG. 6) would be (from Table II) ".020" (.75-.73) or ".0004". The same result would be obtained in figuring the difference in curves 33 and 34 (FIG. 7) and the difference in curves 52 and 53 (FIG. 12) at the same point. While a difference in crown of ".0004" initially appears to be a relatively small one, it may be very significant in rolling a very thin sheet of material to a uniform thickness.

In any of the cases discussed, roll axis crossing, roll bending or roll unbending, the reason for such provision of an effective roll crown is to obtain a series of crowns to suit a range of different materials to be processed on a given calender. Different materials to be processed require different pressures, less crown being required for materials requiring lesser pressure and vice versa. It will be understood that the entire difference between the crown contours, as exemplified by curves C and B, may not be added to or subtracted from a roll, but some predetermined percentage of this difference may be added to or subtracted from a roll in accordance with design considerations of the roll and the types of materials to be processed. While the invention has been disclosed as applied to the bottom roll of a calender, it is to be understood that it is equally applicable where rolls other than the bottom rolls are to be bent or operated with crossed axes to provide an effective crown.

While the invention has been disclosed in various embodiments thereof, it will be apparent that the invention may be practiced with various apparatus designed to effect roll cross axis and roll bending crown compensation, and it is intended to cover in the appended claims all embodiments of the invention and modifications of the disclosed invention which do not depart from the spirit and scope of the invention.

What is claimed is:

1. For use in a calender or like device having a plurality of cooperating rolls and having at least one roll adapted to have its axis crossed with respect to the axis of a cooperating roll to provide an effective crown on said one roll; a calender roll having a contour along its face predetermined by the difference between a crown contour based upon the shape of a uniformly loaded beam between two points of support, and an effective crown defined by the distance between adjacent surfaces of a pair of cooperating uniform diameter rolls arranged for cross axes operation.

2. The calender roll of claim 1 wherein said calender roll has a crown contour along the face thereof predetermined in accordance with the shape of a uniformly loaded beam for a given A/L value of said roll, said crown contour being reduced proportional to the difference between said loaded beam crown contour and an effective crown defined by the distance between adjacent surfaces of a pair of cooperating uniform diameter rolls arranged for cross axes operation, where L is the length of the face of the roll and A is the distance from the one end of the roll face to the center of support of the roll journal at that end.

3. The calender roll of claim 1 wherein said calender roll has a cylindrical contour reduced proportional to the difference between said loaded beam shape for a given

A/L value of said roll and an effective crown defined by the distance between adjacent surfaces of a pair of cooperating uniform diameter rolls arranged for cross axes operation, where L is the length of the face of the roll and A is the distance from the one end of the roll face to the center of support of the roll journal at that end.

4. For use in a calender or like device having a plurality of cooperating rolls and having at least one roll adapted to be bent by applying oppositely directed force couples at opposite ends thereof to define an effective crown thereon having a shape which is substantially an arc of a circle; a calender roll having a crown contour along its face predetermined by the difference between a crown contour which is substantially an arc of a circle and a crown contour based upon the shape of a beam which is uniformly loaded between two points of support.

5. The calender roll of claim 4 wherein said predetermined difference in contour is added to the contour of said calender roll.

6. The calender roll of claim 4 wherein said predetermined difference in contour is subtracted from the contour of said calender roll.

7. The calender roll of claim 4 wherein said calender roll has a crown contour thereon based upon the shape of a beam which is uniformly loaded between two points of support for a given A/L value of said roll, said crown contour being reduced proportional to the difference between said crown contour and a crown contour which is substantially an arc of a circle, where L is the length of the face of the roll and A is the distance from the one end of the roll face to the center of support of the roll journal at that end.

8. The calender roll of claim 4 wherein said calender roll has a crown contour thereon based on the shape of a beam which is uniformly loaded between two points of support for a given A/L value of said roll, said loaded beam crown contour being increased proportional to the difference between said loaded beam crown contour and a crown contour which is substantially an arc of a circle, where L is the length of the face of the roll and A is the distance from the one end of the roll face to the center of support of the roll journal at that end.

9. The calender roll of claim 4 wherein said calender roll has a cylindrical contour reduced proportional to the difference between a crown contour based upon the shape of a beam which is uniformly loaded between two points of support and a crown contour which is substantially an arc of a circle, where L is the length of the face of the roll and A is the distance from the one end of the roll face to the center of support of the roll journal at that end.

10. The calender roll of claim 4 wherein said roll has a cylindrical contour which is increased proportional to the difference between a crown contour based upon the shape of a beam which is uniformly loaded between two points of support and a crown contour which is substantially an arc of a circle for a given A/L value of said roll, where L is the length of the face of the roll and A is the distance from the one end of the roll face to the center of support of the roll journal at that end.
